DESIGN FOR A TOY DOG

Jessie A. Cramer, Muncie, Ind.

Application November 11, 1944, Serial No. 116,281

Term of patent 3½ years

(Cl. D34—2)

To all whom it may concern:

Be it known that I, Jessie A. Cramer, a citizen of the United States, residing at Muncie, in the county of Delaware and State of Indiana, have invented a new, original, and ornamental Design for Toy Dogs, of which the following is a specification, reference being had to the accompanying drawing, forming a part thereof.

Figure 1 is a side view, Figure 2 is a front view, and Figure 3 is a rear view of a toy dog, showing my new design.

I claim:

The ornamental design for a toy dog, as shown.

JESSIE A. CRAMER.
